FUSE

Edwin F. Kiefer, Cleveland, Ohio, assignor to
 National Carbon Company, Inc., a corporation
 of New York

Application December 1, 1931, Serial No. 578,347

18 Claims. (Cl. 200—123)

The invention is a delayed action fuse for electric circuits.

One object is to provide a fuse that will carry a large overload for a short period of time but will 5 blow on a small overload after a longer period of time.

Another object is to provide a fuse that will minimize the arc formed when it blows.

Another object is to provide a fuse that will not 10 deteriorate with age or use.

Other objects are to provide a fuse that is compact, reliable, low in cost, easy to manufacture, and positive in action.

Other aims, objects, and novel features will be 15 manifest by the following specification and the accompanying drawing, of which:

Fig. 1 is a vertical section through my fuse installed in a plug mounting, and

Fig. 2 is a longitudinal section of my fuse installed in a cartridge mounting.

My fuse comprises two pieces of electrically conductive carbon, such as carbon rod, held together by a joint of fusible alloy. The carbon rod is preferably cylindrical and the joint is preferably 25 between the ends.

The fusible alloy may be ordinary solder composed of a mixture of substantially equal parts of lead and tin or it may be any other similar or equivalent alloy adapted for the purpose. Preferably the fuse is provided with means, such as a spring, to separate the carbon sections when the fusible joint therebetween has melted, and this spring may carry the electric current to the fuse, or a separate conductor may be provided to carry 30 either all or part of the current. The fuse may be mounted in any suitable holder, such as a plug or cartridge, or it may be mounted directly upon some portion of the apparatus it is adapted to protect.

One example of my invention as installed in a fuse plug is shown in Fig. 1. The plug comprises a dielectric body 10 of any suitable material, such as porcelain or bakelite, having an axial opening 11 therethrough closed at the top by a transparent window 12 carried by a supporting frame 13 and closed at the bottom by a conical dielectric tip 14 held to the body 10 by a threaded metal or conductive shell 15 forming one terminal of the fuse. Secured to the center of the conical tip 14 is a conductive metal holder 16 forming the other terminal of the fuse plug, and a conductive separating spring 17 is attached to the outer edge of the metal shell 15 by a joint of solder or compression and extends inward through the body 10.

A fuse 18, comprising a cylindrical carbon rod 19

having one end thereof joined directly to one end of a similar rod 20 by a joint of solder 21 in contact with both rods, is mounted under tension between the inner end of the separating spring 17 and the metal holder 16. The carbon rods 19 and 20 may be attached to the spring 17 and metal holder 16 by any suitable means, such as a joint of solder or compression.

Another example of my invention installed in a cartridge fuse is shown in Fig. 2. The cartridge 10 comprises a tubular dielectric body 22 of any suitable material, such as fiber or bakelite. A conductive metal cap 23 is mounted upon one end of body 22 by a threaded or compression joint 24 and a similar cap 25 is mounted upon the other end of the body 22 in a similar manner.

A conductive separating spring 26 is secured to the inner side of cap 25 by suitable means, such as a joint of solder 27, and my improved fuse comprises a carbon rod 28 having one end thereof directly joined to one end of carbon rod 29 by a joint of solder 30 which is mounted under tension between the inner end of separating spring 26 and conductive cap 23. The fuse may be secured to the cap 23 by any suitable means, such as a joint of solder 31 and it may be secured to the separating spring 26 by a similar joint 32. The separating spring 26 may carry the entire current passing between caps 23 and 25 through the fuse or a separate conductor 33 may be provided between rod 29 and cap 25 to carry a part of the current.

When in use the fuse plug or fuse cartridge may be held by a suitable fuse block or other mounting well known in the art and ordinarily used with fuses of the form shown. When in use the electric current passes from one terminal to the other through my fuse and when the fuse is sufficiently overloaded the heat generated by the passage of electric current through the carbon rods melts the joint of fusible alloy or solder by which they are joined, and the separating spring draws them apart. As the arc formed at the time of separation is between the carbon rods it will be minimized as this is one of the 45 characteristics of the carbon.

My fuse is entirely different from and possesses many advantages over thermal cut-outs or relays having contacts that are opened by heat generated in a coil of wire having high resistance, and "sneak" fuses in which a piece of fuse wire is melted by heat generated by the passage of current through a coil of high resistance wire. As my fuse has a lower resistance it consumes 50 less current during normal operation, and as the 55

circuit is opened by the rapid separation of carbon contacts, the trouble caused by arcing is much less than in thermal relays.

In sneak fuses and to some extent in all fuses employing an exposed piece of fusible alloy wire, this wire may, after being in use for some time, become covered with a coating of oxide that has sufficient strength to support the fusible metal after it has melted so that it will carry current in excess of that at which it is supposed to blow. In my fuse the fusible alloy is protected by the carbon rods so that it cannot deteriorate or oxidize with age or use. Therefore my fuse is more reliable and positive in action than fuses employing bare fuse wire.

The reliability and desirable characteristics of my fuse are shown by the results obtained from those tested. For instance, it was found that fuses adapted to carry $4\frac{1}{2}$ amperes continuously would blow on a current of 5 amperes after a period of 2 minutes, while on the other hand, these fuses would carry from 2 to 4 times their normal load for a period of 10 to 20 seconds. These results show that this fuse is especially adapted to protect electrical apparatus having inductive windings, such as motors, as it is well known that such devices require a large overload for a short period of time when started, but are liable to be injured by a small overload over a long period of time.

While I have shown my fuse as having two carbon rods joined by a fusible alloy and installed in conventional mounts, it is understood that the fuse may have other forms and be mounted in different ways. Although the carbon elements of the fuse are shown joined end to end, the carbon may have other forms. Furthermore, the area of solder joint between the sections may be varied to vary the characteristic of the fuse.

Where no particular material has been mentioned it is understood that conventional material has been employed. Whether the material has been mentioned or not, it is understood that similar and equivalent materials may be substituted. It is also understood that the general form, shape, and relative arrangement of the parts may be altered without departing from the spirit of the invention or the scope of the claims.

I claim:

1. A delayed action fuse comprising a dielectric body; two conductive terminals mounted on said body; a conductor spring carried by one of said terminals; and a fuse comprising two pieces of carbon rod held together directly by a joint of fusible alloy, mounted under tension between said spring and said other terminal.

2. A delayed action fuse comprising two pieces of cylindrical carbon rod directly held together end to end by a joint of fusible alloy; means for mounting said fuse in a suitable holder; and a spring in said holder for separating said carbon rods when said fusible alloy has been melted.

3. A delayed action fuse comprising two carbon rods held together directly by a joint of solder; means for mounting said fuse in a suitable holder; and means in said holder for separating said carbon rods after said joint has melted.

4. A delayed action fuse comprising two carbon rods held together by a fusible joint; means for mounting said fuse in a suitable holder; a spring in said holder for separating said carbon rods when said joint fuses; and a conductor in parallel with said spring.

5. A delayed action fuse comprising two carbon rods directly held together by a joint adapted to

be fused when said fuse is overloaded, and means for separating said carbon rods when said joint fuses.

6. A delayed action fuse comprising two carbon rods directly held together by a joint of solder. 5

7. A fuse for electrical circuits, comprising two carbon elements directly joined by a fusible alloy.

8. A delayed action fuse comprising two carbon elements directly joined by a fusible joint and mounted under tension. 10

9. A delayed action fuse comprising two carbon elements directly held together by a fusible joint and means for maintaining said joint under 15 tension.

10. A delayed action fuse comprising the combination of two elements adapted to become heated; a joint adapted to be fused by said heat in contact with both of said elements, and means 20 for separating said elements when said joint fuses.

11. A delayed action fuse comprising the combination of two resistance elements adapted to become heated by the passage of electric current therethrough; a joint for holding said elements 25 together adapted to be fused by said heat; and means for separating said elements when said joint fuses.

12. A delayed action fuse comprising a hollow dielectric holder; two conductive terminals 30 mounted on said holder; a conductive spring carried by one of said terminals within said holder; a fuse comprising two cylindrical carbon rods secured under tension in said holder in axial alignment between said spring and one of 35 said terminals; and a fusible alloy united directly to one end of each of said rods to secure them together.

13. A delayed action fuse comprising a dielectric holder having a cylindrical opening therein; 40 a cylindrical fuse in said holder in axial alignment with said opening comprising two carbon rods having substantially flat adjacent ends; a thin layer of fusible alloy united directly to the adjacent ends of said rods; and means for supporting said rods in said holder comprising a spring in said opening secured under tension to one of said rods.

14. A delayed action fuse comprising two carbon rods united by a joint of solder in contact 50 directly therewith; a holder for said fuse; means for mounting said fuse in said holder; and means in said holder for separating said rods when said solder fuses.

15. A delayed action fuse comprising a fusible 55 element; two carbon rods united directly by said element; a holder having an opening therein; and means for mounting said carbon rods in said holder comprising a spring in said opening for separating said rods when said element fuses. 60

16. A delayed action fuse comprising a cylindrical dielectric holder having an axial cylindrical opening therethrough; a conductive cap on each end of said holder over each end of said opening; two cylindrical carbon rods in said holder in axial alignment with said opening; means for securing one of said rods to one of said caps; a fusible alloy united directly with adjacent ends of said rods; a conductive helical spring in said holder in axial alignment with said rods secured 65 under tension between the other of said rods and the other of said caps; and a flexible electrical conductor in parallel with said spring.

17. A delayed action fuse comprising a plug 70 having a cylindrical dielectric body with a cylind-

drical opening therein; a conductive holder extending through said body at the axis of said opening; two cylindrical carbon rods in said body in line along the axis of said opening; a fusible metal united directly with adjacent ends of said rods; means for securing one of said rods to said holder; a metal shell secured to the outside of said body and covering a portion thereof; and a flat conductive spring extending laterally

through the wall of said body with one end secured to said shell and one end secured under tension to the other of said rods.

18. A delayed action fuse comprising two carbon rods and a fusible alloy united directly with each of said rods to secure them together by a joint of adhesion.

EDWIN F. KIEFER.
